(57) **CLAIM**

The ornamental design for a flood and freeze sensor, as
shown and described.

DESCRIPTION

FIG. 1 is a front perspective view of the flood and freeze
sensor according to a first embodiment of the present design;

FIG. 2 is a right-side elevational view of the flood and freeze
sensor of FIG. 1;

FIG. 3 is a left-side elevational view of the flood and freeze
sensor of FIG. 1;

FIG. 4 is a rear elevational view of the flood and freeze
sensor of FIG. 1;

FIG. 5 is a front elevational view of the flood and freeze
sensor of FIG. 1;

FIG. 6 is a top plan view of the flood and freeze sensor of
FIG. 1;

FIG. 7 is a bottom plan view of the flood and freeze sensor
of FIG. 1;

FIG. 8 is a front perspective view of the flood and freeze
sensor according to a second embodiment of the present
design;

FIG. 9 is a right-side elevational view of the flood and freeze
sensor of FIG. 8;

FIG. 10 is a left-side elevational view of the flood and freeze
sensor of FIG. 8;

FIG. 11 is a rear elevational view of the flood and freeze
sensor of FIG. 8;

FIG. 12 is a front elevational view of the flood and freeze
sensor of FIG. 8;

FIG. 13 is a top plan view of the flood and freeze sensor of
FIG. 8;

FIG. 14 is a bottom plan view of the flood and freeze sensor
of FIG. 8;

FIG. 15 is a front perspective view of the flood and freeze
sensor according to a third embodiment of the present
design;

FIG. 16 is a right-side elevational view of the flood and freeze
sensor of FIG. 15;

FIG. 17 is a left-side elevational view of the flood and freeze
sensor of FIG. 15;

FIG. 18 is a rear elevational view of the flood and freeze
sensor of FIG. 15;

FIG. 19 is a front elevational view of the flood and freeze
sensor of FIG. 15;

FIG. 20 is a top plan view of the flood and freeze sensor of
FIG. 15; and,

FIG. 21 is a bottom plan view of the flood and freeze sensor
of FIG. 15.

In the drawings, the broken lines depict environmental
subject matter only and form no part of the claimed design.
